[57] CLAIM

The ornamental design for a back bar merchandiser, as shown and described.

DESCRIPTION

FIG. 1 is a front perspective view of the back bar merchandiser from above and one side;

FIG. 2 is a front elevation thereof; and,

FIG. 3 is a right side elevation thereof, the left side elevation being a mirror image thereof.The bottom and back of the back bar merchandiser form no part of the claimed design.
